FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

STOP-INDEX SYSTEM FOR BORING-MILLS.

1,188,043.

Specification of Letters Patent. Patented June 20, 1916.

Application filed December 3, 1914, Serial No. 875,835. Renewed May 10, 1916. Serial No. 96,712.

To all whom it may concern:

Be it known that I, FREDERICK F. CLARKE, citizen of the United States, residing at Franklin, in the county of Venango and State of Pennsylvania, have invented 5 certain new and useful Improvements in Stop-Index Systems for Boring-Mills, of which the following is a specification.

The object, construction, application and 10 utility of my improved feed-stop index, are herein set forth with sufficient clearness to enable those skilled in the art of boring-mill construction to make and use the same.

The object of this invention is, to provide 15 a boring-mill with a suitable stop-index system for the feed, which will indicate when a certain operation of the machine has reached a predetermined point, or, in other words, when a tool which is in operation 20 has reached a definite point at which its operation should be discontinued.

In boring-mills which employ a turret-head, the turret is supplied with a plurality of tools which operate successively upon 25 the work that is being done, usually, each successive tool proceeding with the work from the point at which the preceding tool ceased to operate. In order to obviate the necessity of making actual measurements 30 of the work, to determine whether a tool has reached the predetermined limit of its operation, the element which causes the feed-actuation, or some other suitable element of the machine, or two such elements, 35 are supplied with a suitable index or indexes which automatically indicate the desired information in said particular.

It is the particular object of this invention to provide a plurality of such indexes 40 and combine them into a readily-readable system, and more particularly to provide means whereby the various indicating-devices employed may be securely locked in their proper positions so that any other-wise possible accidental movement of same 45 will be prevented and the necessary accuracy insured.

The construction whereby I attain said objects, is clearly shown in the drawings, 50 the various figures of which are as follows:

Figure 1 is a front elevation of a portion of one end of the cross-rail of a boring-mill, showing a portion of a feed-screw, with a portion of my improved index-sys-

tem applied thereto, Fig. 2 is a face view 55 of an index-point employed upon said screw, Fig. 3 is an edge view of said point, Fig. 4 is a front elevation of the cross-rail of a boring-mill, supplied with a turret-head and showing my improved system of indexes applied thereto, Fig. 5 is a fragmentary plan view of the turret-slide, the way in which the supplementary indexes are applied thereto, being specially illustrated, Fig. 6 is a fragmentary end 65 view of the cross-rail, showing the way in which my indexes are applied thereto, Fig. 7 is a portion of the scale-element which forms a portion of this system.

The same reference-numerals are applied 70 to identical parts in all the views.

The index-system here shown consists of the combination of what I term the micrometer-element, the function of which is, to indicate minute measurements, as hundredths of an inch or fractions thereof, and a scale-element, the office of which is, to indicate the larger dimensions, such as are 75 easily readable upon a flat scale.

The micrometer-element of the system is 80 applied to the feed-screw, which causes the horizontal feed-movement of the saddle upon the cross-rail, and to the feed-shaft, which causes the vertical movement of the turret-slide within said saddle. The scale-elements of the system could be variously applied to any suitable portion of a stationary element, which is suitably located with reference to said feed-actuated element.

In the drawings, two separate systems 90 are shown, one to indicate the movement of the saddle upon the cross-rail, and the other to indicate the movement of the turret-slide within the saddle. The drawings are so made, for the purpose of being fully 95 explicit, but inasmuch as one system is practically a duplicate of the other, but one system—that relating to the feed of the saddle upon the cross-rail—will be described.

I will now describe in detail the construction and combination of the elements of said system. The feed-screw previously mentioned is indicated by the reference-number 1 in the drawings; said screw is power-driven to cause the feed-actuation of said saddle, and each revolution of said screw will cause a certain definite, prede-

terminated feed-advance of said saddle, which, for the purpose of illustration, we will call one-quarter of an inch. The end of said screw, which projects beyond the 5 cross-rail, is provided with the usual sleeve 2, which adapts the same to be crank-actuated. Upon the inner, reduced portion of said sleeve, is mounted an index-collar 3, which is in proximity to the adjacent end 10 of the cross-rail 4. Said collar 3 is secured to the sleeve 2 by means of the set-screw 5, and by loosening said screw, said collar may, if desired, be adjusted revolubly upon said sleeve, which sleeve is keyed to 15 said screw 1. Collar 3 is provided with clamping-face 6, in which is formed an index-retaining groove 7. In juxtaposition to said clamping-face is mounted the clamping-ring 8, which is likewise provided with an index-retaining groove 9. Said ring is provided with a key-seat 10, which engages the pin 11, thus preventing the ring from revolving. A clamping-nut 12 is provided, and mounted upon a 20 threaded portion of said sleeve and arranged to bear against said ring, to cause the clamping action thereof.

The periphery of the index-collar 3 is provided with suitable graduations 13, and the 30 adjacent face of the cross-rail is provided with a single registry-mark 14, with which said graduations are adapted to register or coincide, and indicate the progress of the feed, within the limit defined by one revolution of said screw.

For each tool that is contained in the turret 15, I provide an index-point 16, Figs. 2 and 3, which in this case will be five points, as shown by the number of sockets 17 in said 40 turret. Said sockets are numbered from 1 to 5 consecutively. Said index-point consists of a strip of resilient sheet-metal, which is formed at one end into a point; the other end is bent at substantially a right angle, then formed into an eye 18, Fig. 3, from whence the metal returns to the original line of the point end. By this construction, two frictional leaves 19 and 20 (Fig. 3) are 45 formed for the purpose which will be presently stated. Said points 16 are mounted upon said index-collar by inserting the leaves 19 and 20 thereof between the clamping-faces of the collar 3 and ring 8 with the eye 18 occupying the retaining-groove 7—9, which prevents the accidental displacement 50 of the points when the nut 12 is unscrewed.

Each of the five points 16 is numbered upon the outer face thereof, to denote to which turret-socket it relates, and before the 60 operation of the boring-mill is started upon a certain piece of work, points 16 are adjusted circumferentially of collar 3, to denote the point at which the operation of the tool to which it relates is to be discontinued. Said adjustment is accomplished by loosen-

ing nut 12, and moving said points as desired; the frictional contact of leaves 19 and 20 against the clamping-faces of the members 3 and 8 will retain said points temporarily in place until all of said points are 70 suitably adjusted, and when the adjusting operation is complete, nut 12 is tightened, thus firmly clamping said points in their respective positions. Now, as the operation of the machine proceeds, and as the various 75 index-points, as they travel with the collar 3, pass the registry-mark 14, they will respectively denote or indicate the distance of travel of the tool carried by the correspondingly-numbered socket of the turret. In 80 many cases, the distance which a given tool must travel in order to accomplish its allotted work, will be more than the distance represented by one revolution of the screw 1 and collar 3, hence it becomes necessary to 85 provide supplementary means to indicate such a requirement. Said supplementary means consists of a scale 21, which is attached to the cross-rail upon which the saddle 22 travels, an enlarged view of which 90 scale is shown in Fig. 7. Affixed to the edge of said saddle, in close proximity to said scale, is an index 23, which indicates upon scale 21 the total distance traveled by said saddle. Upon said scale are mounted five 95 index-points 24, which correspond in number to the number of sockets in said turret, each also being correspondingly numbered. Said points are mounted upon said scale 21 and adjustable longitudinally thereof. At 100 the back of said scale is located a locking-device for said points, which consists of a rod 25—Fig. 6—for which a groove 26 is formed in the cross-rail; a flat 27 is milled upon said rod, and when the same is turned 105 so that said flat is in juxtaposition to said scale, said points may be freely moved longitudinally of said scale and each of said points adjusted to a position to indicate approximately the stop-point of each tool to 110 which it relates; when said adjustment is complete, a partial turn of said rod by means of the lever 28 will cause the unmilled or normal surface of said rod to bear firmly upon all of said points, thus simultaneously 115 locking them all, and each one in its respective indicative position, thus preventing any accidental displacement of same.

The combination of the two indicating-elements here shown, is necessary, for the 120 following reasons: In present-day machine-tool operations, the employment of dimensions such a hundredth, half a hundredth or even a thousandth of an inch, are matters of every-day practice, and such dimensions cannot be determined with the scale-element here shown, but they can readily be measured and indicated by the micrometer-element. Taken alone, however, its limit of indicated measurement is one revolution, or, 130

as previously stated, one quarter of an inch,— hence to approximately record extended dimensions, the scale must be employed.

Fig. 5 is an enlarged plan view of the 5 scale and locking device, as it is applied to the turret-slide 29, the scale being shown at 30, the adjustable points at 31, the index at 32, the locking-rod at 33, and the manipulating-lever for said rod at 34; all of which 10 operate in supplemental conjunction with the micrometer-index upon the feed-rod 35 which feeds said turret-slide vertically.

It will be readily understood by those skilled in the art to which this invention 15 relates, that the horizontal feed of the tools and the vertical feed of the same are not usually, if ever, simultaneously employed, and that when the turret-slide is moving vertically in the saddle, said saddle is stationary. By keeping this point in mind, a 20 clearer understanding of the invention, as defined in the claims, will result.

I claim the following:

1. In a boring-mill equipped with a plurality of tools arranged to operate successively upon the work to be performed, an index-system consisting of the combination of a micrometer-element and a scale-element, arranged to conjointly indicate the 30 extent of the work of each of said tools, said micrometer-element consisting of a graduated collar carried by a revolute element which causes the feed-actuation of said tools, index-points adjustably carried by 35 said collar, a fixed registry-mark with which said points successively register, means for simultaneously locking all of said points in their respective indicative positions, a movable tool-carrying element, a stationary element upon which said carrying-element travels, a graduated scale affixed to said stationary element, in close proximity to said carrying-element, a plurality of adjustable index-points mounted upon said scale, an 40 index carried by said tool-carrying element, adapted to denote approximately, by successive registry with said scale-points, the extent of the work of each of said tools, and means for simultaneously locking said 50 scale-points in their respective denoting-positions.

2. In a feed-stop index-system for boring-mills, an element of such system, comprising a collar provided with graduations upon 55 the periphery thereof, secured to the feed-screw, one lateral face of said collar being

arranged to constitute a clamping-face for the engagement of adjustable index-points, index-points mounted upon said collar, in contact with said face, a clamping-ring 60 mounted in juxtaposition to said clamping-face, and adapted to coöperate with said collar in the engagement of said points, and a nut adapted to actuate said ring into the clamping-position. 65

3. In a feed-stop index-system for boring-mills, an element of such system consisting of a scale secured to a stationary element of such mill, in proximity to a feed-actuated element, a plurality of index-points mounted upon said scale and adapted to be moved longitudinally thereof, locking-means for said points, arranged to simultaneously lock all of same in their respective adjusted positions, and a point carried by 70 said feed-actuated element, arranged to register successively with said index-points, and indicating the progress of said feed-actuated element.

4. In a feed-stop index-system for boring-mills, an element of such system consisting of an index-point composed of resilient sheet-metal which is formed at one end into a point, and in proximity to the other end thereof is bent at a right angle, then formed 85 into an eye, then returned to the original line, whereby two parallel leaves or frictional members are formed, adapted to temporarily retain said element between two adjacent faces of a clamping-device, in 90 combination with a clamping device consisting of a collar carried by a revolute element which is operable to cause the feed-actuation of the tools of said mill, a lateral face of said collar adjacent to the periphery 95 thereof being formed into a clamping face, there being an annular groove adjacent to said clamping face for the reception of said eye, a coöperating clamping ring with a lateral face thereof arranged in juxtaposition 100 to said first-mentioned clamping face, said clamping faces being adapted to bear upon the respective sides of said parallel leaves, and means operable to actuate said clamping ring into its coöperative clamping position 105 with said collar, for the purpose set forth.

In testimony whereof I affix my signature in presence of two witnesses.

FREDERICK F. CLARKE.
